(57) **CLAIM**

The ornamental design for a flashlight, as shown and described.

DESCRIPTION

FIG. 1 is a front perspective view of the flashlight;

FIG. 2 is a front plan view of the flashlight;

FIG. 3 is a back view of the flashlight;

FIG. 4 is a side view of the flashlight;

FIG. 5 is a top view of the flashlight;

FIG. 6 is a bottom view of the flashlight;

FIG. 7 is a perspective view of the flashlight wherein the flashlight is moved in a second orientation;

FIG. 8 is a front view of the flashlight in the second orientation;

FIG. 9 is a back view of the flashlight in the second orientation;

FIG. 10 is a side view of the flashlight in the second orientation;

FIG. 11 is a top view of the flashlight in the second orientation;

FIG. 12 is a bottom view of the flashlight in the second orientation; and,

FIG. 13 is a perspective view of the flashlight being moved from the first orientation to the second orientation.

The broken line showing is for illustrative purposes only and forms no part of the claimed design.
